Baldwin, Davidson & Wright.

UNITED STATES PATENT OFFICE.

DANIEL P. MCQUEEN, OF SCHENECTADY, NEW YORK.

STEAM-BOILER.

SPECIFICATION forming part of Letters Patent No. 442,080, dated December 2, 1890.

Application filed June 23, 1890. Serial No. 356,373. (No model.)

To all whom it may concern:

Be it known that I, DANIEL P. MCQUEEN, a citizen of the United States, residing in the city and county of Schenectady, and State of New York, have invented certain new and useful Improvements in Steam-Boilers, of which the following is a specification.

My invention more especially relates to boilers of the tubular class. Its object is to secure a strong, simple, and efficient boiler the tubes of which may be placed close together, thus securing large heating-surface in a comparatively small space, and providing for a free circulation of the water and steam without diminishing the strength of the boiler, while at the same time permitting the tubes to be readily accessible for cleansing, inspection, insertion, or removal. These ends I attain by constructing the boiler with a double shell, through which the water-tubes pass at both ends, which are protected by removable caps or plugs, the tubes being perforated so as to open into the space between the shells, thus affording effective circulation. These tubes thus constructed may constitute a fire-grate, as well as part of the water-heating surface in the upper part of the fire-box.

The subject-matter claimed is hereinafter specified.

Unless otherwise indicated the parts are of usual well-known construction.

The accompanying drawings represent so much of a boiler embracing my improvements as is necessary to illustrate the subject-matter herein claimed.

Figure 1 represents an end elevation of one form of my improved boiler with part of the casing broken away to show the internal construction; Fig. 2, a vertical central longitudinal section on the line 2 2 of Fig. 1.

In the drawings, which show a boiler of the locomotive type, the shell A is shown as composed of parallel inner and outer plates a a', braced by stay-bolts A', the space between the plates constituting a water-space. The front head A² is provided with the usual fire-doors B, opening into the furnace C, from which the products of combustion escape through the uptake C' after passing among the water-tubes E, as hereinafter described. The grate is shown as consisting of a series of parallel tubes D', extending entirely through both shells at each end, which ends are covered by caps d, screwed thereon,

which constitute both packing and jam-nuts. 55 The tubes are preferably secured in position by expanding them to fit tightly in the holes in the plates a a', through which they pass. These tubes where they pass through the water-spaces of the boiler have 60 perforations d' in them to permit the water to circulate freely therethrough. A series of parallel water-tubes E is in like manner secured in the upper part of the fire-box, their ends being provided with screw-caps e. Slits 65 or apertures e' are cut in these tubes in that portion corresponding with the water-spaces, the area of these apertures being preferably equal to that of the tubes, so as to permit of a free circulation through them and the water legs or spaces. These tubes, it will be observed, take the place of the ordinary stay-bolts, and may consequently be placed close together without weakening the boiler. They can readily be inspected or cleansed by removing the caps, which can be readily screwed into or out of place. 70

The water-line is above the tubes in the upper shell of the boiler, and the steam-drum F is connected with the steam-space F' by 80 tubes or passages f.

Having thus described my improved steam-boiler, what I claim therein as new and as of my own invention is—

1. The combination, substantially as hereinbefore set forth, of the double shell inclosing the fire-box, the water-grate tubes extending through the fire-box and through both shells, devices for closing the ends of the tubes, and lateral perforations or openings in 90 the tubes between the shells to permit the circulation of water through the tubes and between the shells.

2. The combination, substantially as hereinbefore set forth, of the double-shell boiler, 95 the fire-box, the tubular grate-bars, and the water-tubes, both grate-bars and tubes projecting at each end through the boiler-shell and provided with lateral openings into the space between the shells, so that the grate-bars and tubes may be included in the same circulation system.

In testimony whereof I have hereunto subscribed my name.

DANIEL P. MCQUEEN.
